MAGAZINE AND FEED MEANS FOR FASTENER-APPLYING IMPLEMENTS

Russell B. Edmond, Westerly, R. I., assignor to Bostitch, Inc., Stonington, Conn., a corporation of Rhode Island

Application September 13, 1955, Serial No. 534,078

8 Claims. (Cl. 1-3)

This invention relates to improvements in fastener-applying implements and more particularly to the magazine therefor for holding a supply of fasteners such as U-shaped tape with means for advancing them in the magazine to feed them individually to the fastener-applying means.

One object of the invention is to provide an implement of the type indicated having a relatively long arm with staple-driving means at its forward end and constituted as a magazine for containing a large supply of staples with means for feeding them to said driving means.

Another object is to provide a staple-pusher slidably on the magazine-arm to feed the staples forwardly therewith along with resilient means mounted above said arm and connected to said pusher to propel it forwardly on the arm.

Another object is to provide a hinged member extending above the magazine-arm for mounting a relatively long helical spring adapted for connection to the pusher for propelling it on the arm and releasable therefrom by raising said member to permit the pusher to be removed from the magazine for loading staples into the rearward end thereof.

Another object is to construct said pivoted member in the form of a hollow casing or sheath for housing a relatively long length of the helical spring for adapting it to operate the staple-pusher without undue tension thereon.

Another object is to provide a relatively long spring having its major length encased in said hollow member with a lesser portion of its length extending thereabove and connected by manually-releasable means to the pusher or propelling it while being conveniently retractable for disconnecting it from the pusher.

Another object is to provide an implement of the type indicated adapted for continuous use over long periods of time without reloading it with fasteners or staples.

A further object is to provide an implement of the type indicated of simple, strong and rugged construction with its parts not liable to displacement or getting out of order during use.

The invention is described in the following specification illustrated by the accompanying drawings. In the drawings:

Fig. 1 is a side elevational view of the present improved fastener-applying implement or stapler shown as prepared for use with its magazine loaded with staples;

Fig. 2 is a side elevational view of the magazine-arm carrying the staple-driving mechanism and illustrating the device with the spring-enclosing arm elevated and the pusher removed for loading staples into the magazine;

Fig. 3 is a somewhat enlarged perspective view of the staple-pusher shown as removed from the implement;

Fig. 4 is a part-sectional side elevational view of the magazine-arm of the implement showing the hollow hinged member for containing the main length of the pusher-propelling spring;

2

Fig. 5 is a plan view of the implement shown with the magazine-arm partly broken away;

Fig. 6 is a longitudinal sectional view of the staple-driving means at the forward end of the magazine-arm;

Fig. 7 is a transverse sectional view of the head of the implement taken on line 7-7 of Fig. 1; and

Fig. 8 is a transverse sectional view of the rearward end of the magazine-arm taken on line 8-8 of Fig. 1.

Many varieties of fastener-applying means, more particularly hand-operated staplers, have relatively short magazine-arms which can contain only a limited supply of staples so that they require frequent reloading during use. One object of the present invention is to provide a stapler having a magazine capable of holding a much larger supply of staples; for example, several times the usual number of staple "sticks" or supply cartridges in which the staples are packaged. The usual method of supplying staples to the applying means consists in providing a slide or staple-pusher with a helical spring for propelling it in or along the magazine to feed the staples singly to the driving means. It is obvious that in a device of the present type having a much extended or relatively long magazine-arm the spring for propelling the pusher must be proportionally lengthened and the present invention provides for such extension of the spring while sheathing it throughout the major portion of its length. The present improvement accomplishes this purpose by providing a hollow member, for example, a tube for containing the major length of the elongate spring, said member being hinged above the magazine and provided with a manually-slidable member thereon connected to the end of said spring and adapted for engagement with the staple-pusher to propel it along the magazine-arm.

As herein shown, the present stapling implement is generally similar to that disclosed in United States Letters Patent No. 2,429,269 of October 21, 1947, and as shown in Fig. 1 of the present drawings it may be constituted by a base 2 adapted to be seated on a table, bench or other support and mounting clincher means 3 at its forward end. The rearward end of the base 2 may be provided with an upstanding abutment or bearing 4 for pivotally mounting a magazine-arm 5 having a head 7 at its forward end containing staple-driving means 6. As herein shown, the arm 5 is pivoted to the base 2 by means of a cross-pin 10 extending transversely through the bearing 4 and engaging through an elongated hole 11 (Fig. 4) at the rearward end of the magazine-arm 5.

A pair of screws 12, 12 threadingly engaging vertical bores in the rearward end of the arm 5 have beveled points at their ends in contact with the sides of the pin 10 (Fig. 1) to adapt them for adjustment to displace the arm 5 longitudinally for alining the staple-driver 15 at the forward end of the implement with the clincher-means 3 on the base 2; this form of construction being shown in United States Letters Patent No. 2,698,938 of January 11, 1955. The magazine-arm 5 is normally held with its forward end raised above the base 2 as shown in Fig. 1 by means of a slidable plunger-pin 13 engaging thereunder and forced upwardly by a spring 14 pocketed in the base.

The magazine-arm 5 is preferably constructed in the form of a solid, metal bar 20 of inverted T-shape in cross-section (Fig. 8) with its central upstanding portion of suitable width to serve as a core 22 for supporting the staples 5 in straddled relation thereon while likewise slidably supporting a staple-pusher 25. The arm 5 is constituted as a staple-magazine with overlying side plates 26 formed from sheet-metal (Fig. 8) with lower offset wing-ports 27 extending along the projecting sides of the bar 20 and fixedly secured thereto as by welding or riveting.

From the lower offset-wing-portions 27 the side plates 26 extend upwardly with their upper portions bent inwardly in flanges 28 overlying the core 22 of the bar 20 with a clearance thereabove for the crossbars of the staples s and the top of the pusher 25. The flanges 28 serve as hold-down means for preventing the staples s from riding up on the core 22.

At the forward end of the arm 5 the head 7 is constituted by opposite plates 30 fastened in spaced-apart relationship (Fig. 7) and held in place abutting the sides of the bar 20 by bolts 31, 32 (Fig. 1) with nuts 33 screwed onto their ends. The inner faces of the plates 30 are lined with thinner plates 34 and the upper bolt 32 passes through a sleeve 35 which holds the upper portions of the plates 30 in spaced-apart relationship (Fig. 7). At their lower ends the plates 30 have projections or teats 36 interfitting with holes 37 for holding the plates against longitudinal displacement on the arm 5. The inner faces of the plates 30 are mortised at 38 to provide clearance for the legs of the staples s and the sides of the pusher 25 at the forward end of the arm 5.

The outer faces of the plates 30 are formed with vertical grooves 39 (Fig. 1) for receiving the inturned flanges 40 of a hollow plunger 50 (Fig. 5) to adapt it to slide up and down on the head 7. The plunger 50 has a knob 51 overlying its upper end and joined to the sides thereof by a cross-pin 52. Slidable in vertical grooves 53 on these inner faces of the plates 30 of the head 7 is the driver-blade 15 connected to the plunger 50 for reciprocation thereby. A stud 56 is riveted through a hole in the front wall of the plunger 50 with the end of its reduced portion 57 projecting through a hole in the driver-blade 15 for connecting it with the plunger. A helical spring 60 having its upper portion surrounding a pin 61 that projects downwardly from the knob 51 has its lower end supported on pointed ears 62 (Fig. 4) projecting inwardly from cut-out portions of the inner plates 34 which line the faces of the main plates 30. The spring 60 is contracted (Fig. 6) as the plunger 50 is depressed to force the driver 15 downwardly for driving a staple into the work; the spring 60 being caused to expand when pressure on the knob 51 is released to raise the plunger 50 into inoperative position (Fig. 4). A pawl 65 rockably mounted on the front wall of the plunger 50 is acted upon by a spring 66 fastened at the top by a screw 67 and plate 68 to force its lower end through an opening 69 in the front of the wall of the plunger. The pawl 65 is adapted to be engaged with detent-shoulders 70 on projections 71 at the upper edges of the plates 30 to limit the upward sliding movement of the plunger. These and the remaining details of the staple-driving mechanism have no direct connection with the present invention and therefore are not further described herein. A retractable staple-supporter 72 (Fig. 6) at the forward end of the core 22 is operated by a pocketed spring 73 for guiding the descent of the staples s through the grooves 53 which form the throat for the staple in the foot 74 on the arm 5.

Referring particularly to the perspective view (Fig. 3) the staple-pushers 25 may be constructed of relatively thin sheet-metal folded to provide a flat top with downwardly bent runners 75 adapted to straddle the sides of the core 22 on the magazine-arm 5. An inclined rib 76 formed by bending the metal into inverted U-shape and extending centrally of the top of the pusher 25 serves to stiffen and strengthen its structure. At its rearward end one side of the pusher 25 is slotted and the metal bent upwardly to form a vertical lug 77 having a rounded projection 78 at its upper rearward end. The lug 77 is preferably reinforced by an overlapping thicker piece of metal shaped to the same contour and brazed or welded to its face.

The staple-pushers 25 is propelled forwardly on the core 22 by means of a relatively long helical spring 80 having the major portion of its length sheathed in a tubular member 85 (Fig. 4). The tubular member 85 is

welded or otherwise suitably fastened to the top of a hinge-member 86 that is pivoted on a pin 87 held in holes in the lining plates 34 (Fig. 7) in the head 7 of the implement. That portion of the spring 80 housed in the hollow member 85 has one end anchored to a pin 88 held in holes at the end of said member (Fig. 4) with a portion of its length looped around a pulley 90 journaled on a pin 91 extending between the lining plates 34. From the pulley 90 the spring 80 reaches rearwardly with its end formed as a hook 92 for connecting it to an eye 94 on the end of a sleeve-like finger-grip 95 slidably mounted on the tubular member 85 (Figs. 4 and 5). The finger-grip 95 is substantially spool-shaped with beveled flanges 96 and 97 at its ends, the rim of the forward flange 96 being adapted to engage under the projection 78 of the lug 77 at the rearward end of the pusher 25. The spring 80 is thus adapted to propel the pusher 25 forwardly on the magazine-arm 5 for feeding the staples s to deliver them singly to the applying means. A resilient bumper 98 in the form of a washer constructed of rubber or the equivalent surrounds the tubular member 85 abutting the end of the hinge-member 86. The bumper 98 is adapted to take the thrust of the sliding finger-grip 95 as the latter is drawn forwardly on the tubular member 85 when it is released from the pusher 25 after the hinge-member 86 is swung upwardly as indicated in Fig. 2. At this juncture, practically the full length of the spring 80 is sheathed in the hollow member 85. Likewise, during the advance of the staple-pushers 25 for feeding the staples forwardly in the magazine the spring 80 will be increasingly drawn into and sheathed in the member 85.

The structure and arrangement of the parts of the implement having been described in detail, its method of operation is explained as follows: To prepare the machine for operation the slidable member 95 is grasped in the fingers and retracted to release its flange 96 from under the projection 78 on the lug 77 at the end of the pusher 25. The tubular member 85 is then swung upwardly by pivoting its hinge 86 on the pin 87 (Fig. 2). Upon release of the finger-grip 95 from the pusher 25 the spring 80 will slide said member forwardly on the member 85 until it strikes against the bumper 98. After the finger-grip 95 has been released from the pusher 25 the pusher may be withdrawn from the rearward end of the magazine arm 5 for loading it with staples which are usually packaged in "stick" form as refills S such as shown in Fig. 2. Several of such staple-sticks, depending on their length, may be inserted into the magazine by sliding them forwardly on the core 22, the end of which preferably projects a slight distance rearwardly from the magazine.

After a suitable number of staple-sticks have been inserted into the magazine on the arm 5 the staple-pushers 25 is entered into its rearward end to engage the rearmost staple in the supply, whereafter the tubular member 85 is swung back into position above the arm 5 and the finger-grip 95 reacted therewith to engage its flange 96 with the projection 78 on the pusher. The machine is then ready to operate and the staples s may be successively driven into the work by depressing the plunger-knob 51 to slide the plunger 50 which actuates the driver-blade 15.

After the magazine has been filled with staples in the manner explained above the machine may be operated by placing the work, such as a sheaf of papers or any other articles to be fastened together, in position overlying the clincher-means 3 on the base 2. The arm 5 is normally maintained with its forward end rocked upwardly by the spring-pressed plunger 13 in the bearing 4 on the base 2 and as the plunger-knob 51 is depressed the arm will first be carried down to seat its foot 74 against the top of the work. Continued pressure on the knob 51 will then slide the plunger 50 downwardly to cause the driver-blade 15 to descend against the crown of a staple s to force it through the grooves 53 forming the throat and drive it through the work with its legs clinched against the under side thereof. When pressure on the knob 51 is released the spring 60 will

expand to return the plunger 50 into its upper inoperative relationship and the spring-pressed plunger 13 will raise the magazine-arm 5 above the base 2 as shown in Fig. 1. The implement is then ready for another operation as the staple-pusher 25 is propelled forwardly by the spring 80 to feed another staple into the grooves 53 beneath the lower edge of the driver 15.

When it is not desired to clinch the legs of the staple the present improved magazine-arm 5 may be used without the base 2 by simply withdrawing the pin 10 which connects the arm with the bearing 4 on the base. That is to say, the magazine-arm 5 with its stapling head 7 may be used as a tacker to drive staples through the work and into other objects by simply disconnecting the arm from the base 2.

It will be observed from the foregoing specification that the present invention provides a magazine for fastener-applying implements capable of containing a large supply of fasteners such as staples with especially convenient means for loading it therewith. Due to the extreme length of the magazine-arm it is necessary to employ a relatively long spring to propel the staple-pusher in the magazine for feeding the staples therealong without undue pressure thereagainst. In the present ingenious construction the major portion of the extended pusher-propelling spring is housed within a tubular support which sheathes it and at the same time provides a convenient means for releasably connecting the spring to the staple-pusher. The connection between the finger-grip and pusher is also adapted for most convenient release and the hinged member carrying the spring may be rocked upwardly out of the way when the staple-pusher is withdrawn from the magazine for loading the staples thereinto. Likewise, when the hinged spring-carrying member is rocked downwardly to place the spring in operative relationship the finger-grip may be readily attached to the staple-pusher by practically only a single movement of the hand. When thus connected with the pusher the spring, being of a very considerable length or substantially twice the length of the magazine, will operate without undue tension on the pusher liable to throw the staples out of alinement or otherwise impede their progress through the magazine. It will also be observed that the structure of the implement is extremely simple and compact with the operating parts so designed and co-ordinated as to prevent disorganization or getting out of order.

While the invention is herein shown and described as applied to a hand-operated stapler of conventional type, it is to be understood that the improved magazine may be used with other types of stapling devices, either hand-operated or power-driven, without departing from the scope of the accompanying claims. Therefore, without limiting myself in this respect, I claim:

1. In a fastener-applying implement comprising a hollow magazine for containing fasteners and a pusher for feeding the fasteners therein, the combination of a member hinged at the forward end of said magazine and normally extending rearwardly in spaced relation above said magazine, a helical spring doubled on itself and extending longitudinally of said member with one end anchored to the rearward end of said member, a member slidably on said hinged member and connected to the opposite end of said spring, and means on said slidably member for manually engaging it with said pusher to propel the pusher forwardly in the magazine.

2. In a stapling implement having a longitudinally-extending magazine for receiving staples and a pusher slidably mounted on said magazine for feeding the staples therealong, the combination of a member connected to the forward end of the magazine by a hinge and extending longitudinally above said magazine, a helical spring of substantially twice the length of said last-named member when extended, one end of said spring being anchored to the outer end of said member, a finger-grip slidably mounted on said spring-carrying member, said spring

being doubled on itself with one length extending toward the hinge of said member and its opposite length extending in the reverse direction with its end fastened to said finger-grip, and manually releasable means for engaging said finger-grip with the pusher to propel it longitudinally of the magazine.

3. In a fastener-applying implement comprising a magazine for holding a supply of fasteners and a pusher slidable on said magazine for feeding the fasteners therein, the combination of a hollow member hinged at the forward end of said magazine and extending longitudinally thereabove, a helical spring housed in said hollow member with one end anchored at the outer end of said hollow member, a manually-operable member slidable on said hollow member, said spring doubled on itself in a loop supported at the forward end of said magazine with one length extending rearwardly and connected at its end to said slidable member, and means for releasably engaging said slidable member with the pusher to propel it forwardly in the magazine.

4. In a fastener-applying implement having a magazine for containing fasteners and a pusher for feeding the fasteners longitudinally thereof, the combination of a tubular member hinged to the forward end of said magazine to adapt it to extend rearwardly thereabove, a helical spring housed in said tubular member with one end anchored to the rearward end of said tubular member, means at the forward end of the magazine for supporting said spring doubled on itself with a length thereof extending rearwardly, and a manually-operable member slidably mounted on said tubular member and connected to the end of the rearward length of said spring for sliding said slidably member along said tubular member, said slidably member being manually engageable with said pusher for propelling it to feed the fasteners in said magazine.

5. In a fastener-applying implement embodying a magazine for holding fasteners and a pusher slidable for feeding the fasteners therealong, the combination of a tubular member hinged at the forward end of said magazine to extend rearwardly thereabove while adapting it to be pivoted to raise it from said magazine, a helical spring housed in said tubular member with one end anchored at the rearward end of said tubular member, said spring being supported at the forward end of said tubular member with a length doubled back to extend rearwardly above said member, a finger-grip slidably mounted on said tubular member and connected to the end of said rearwardly-extending portion of said spring to cause said finger-grip to slide forwardly on said member, and means on said finger-grip releasably engageable with said pusher for propelling it forwardly in the magazine.

6. In a stapling implement having a longitudinally-extending magazine for staples and a pusher slidable on said magazine for feeding the staples therealong, the combination of a tubular member hinged at one end of said magazine to adapt it to extend longitudinally thereabove, a helical spring of substantial length housed in said tubular member with one end anchored at the outer end of said member, a pulley at the forward end of said magazine with said spring looped therearound to arrange one length thereof extending rearwardly therefrom, a finger-grip connected to the end of the last-named length of spring for sliding said finger-grip on said tubular member, and means on said finger-grip releasably engageable with said pusher to propel it in the magazine for feeding the staples therealong.

7. In a stapling implement having a longitudinally-extending magazine for staples, and a pusher slidable on said magazine for feeding the staples therealong, the combination therewith of a hollow member hinged above said magazine and extending longitudinally thereof, a helical spring partly contained in said hollow member and anchored at its end to the free end of said hollow member, means for directing a length of said spring in the opposite direction from that of the length contained

in said hollow member, means slideable on said member and connected to the rearward end of the last-named length of said spring, and means for releasably engaging said slideable member with said pusher for propelling it along said magazine.

8. In a fastener-applying implement having a longitudinally-extending magazine with a pusher slideable on said magazine for feeding fasteners therewith, the combination of a tubular member hinged at one end of said magazine and extending rearwardly longitudinally therewith, a helical spring of substantial extent having its major length housed in said tubular member with one end anchored to the rearward end of said tubular member, a pulley journaled on said magazine to support said spring looped therearound with a length extending rearwardly 15 therefrom, a sleeve slideable on said tubular member and

5
connected to the end of the rearwardly-extending length of said spring for sliding said sleeve on said tubular member, and means for releasably engaging said sleeve with said pusher to propel it longitudinally of the magazine.
